UNITED STATES PATENT OFFICE

157,660

LIQUID MEDICINAL DISPENSING MACHINE

Frank J. Cozzoli, Plainfield, N. J.

Application November 26, 1948, Serial No. 149,821

Term of patent 7 years

(Cl. D52—2)

To all whom it may concern:

Be it known that I, Frank J. Cozzoli, a citizen of the United States, residing at Plainfield, in the county of Union and State of New Jersey, have invented a new, original, and ornamental Design for a Liquid Medicinal Dispensing Machine, of which the following is a specification, reference being had to the accompanying drawing, forming part thereof.

Fig. 2 is a side elevational view of the machine shown in Fig. 1. The design of the opposite side of the machine is substantially identical to the side shown.

Fig. 3 is a plan view of the machine illustrated in Figs. 1 and 2.

I claim:

The ornamental design for a liquid medicinal dispensing machine, substantially as shown and described.

FRANK J. COZZOLI.
